UNITED STATES PATENT OFFICE

117,232

DESIGN FOR A SPARK PLUG

Archie C. Lipp, Akron, Ohio, assignor to The B. F. Goodrich Company, New York, N. Y., a corporation of New York

Application August 30, 1939, Serial No. 86,969

Term of patent 14 years

To all whom it may concern:

Be it known that I, Archie C. Lipp, a citizen of the United States, residing at Akron, in the county of Summit and State of Ohio, have invented a new, original, and ornamental Design for a Spark Plug, of which the following is a specification, reference being had to the accompanying drawing, forming a part thereof, of which:

The figure shows a side elevational view of a spark plug illustrating my new design.

I claim:

The ornamental design for a spark plug, as shown.

ARCHIE C. LIPP.
